AIR CONDITIONER

Albert Tonkin, Cloquet, Minn., assignor of two-thirds to J. L. Monnahan, Minneapolis, Minn.

Application August 12, 1936, Serial No. 95,545

2 Claims. (Cl. 257—7)

This invention relates to air conditioning means for automobiles, the principal object being to utilize the cooling effect of the expansion of the fuel employed in the operation of the motor of the automobile.

Still other objects and advantages of the invention will appear in the following description thereof.

Referring now to the accompanying drawings, forming part of this application, and wherein like reference characters indicate like parts:

Figure 1 is a diagrammatic view of the preferred arrangement embodying the invention.

Figure 2 is a side elevation of the elements of the invention located upon an automobile.

The invention is particularly applicable to a self propelled vehicle in which natural gas or other liquid fuel under high pressure is employed, as for example in tanks or the like which are replaced from time to time, in supplying the vehicle with fuel.

In the drawings, 1 represents the motor of the vehicle, 2 the water cooling radiator for the motor, 3 the pump for circulating the motor cooling water, 4 a hot-water radiator for conditioning the air within the vehicle body, 5 is an expansion tank, and 6 the tank of compressed liquid gas.

While I have illustrated the radiator 4 as having but three loops or bights of coil therethrough, for passage of gas to the motor, it is evident that this is only diagrammatic and there may be any desired number of such loops or coils as circumstances may require. In this radiator is illustrated an air vent at 7 which is common in such radiators. The pipe connection from the motor to the upper portion of the radiator 4 is illustrated at 8, it having a branch 9 which leads to the expansion tank 5, and through which the hot water is optionally circulated and controlled as by the shut-off valve illustrated at 10 in the pipe line 8.

11 represents the return or cold water pipe leading from the lower portion of the radiator 4 to the intake of the water circulating pump 3, and thence to the radiator 2 and back to the motor 1, which is the reverse of that which is common in water circulating heating devices for motor vehicles. However in the branch pipe 12 forming the connection between the pipe 11 and the radiator 4 is installed a shut-off valve 13 so that by the closing of these two shut off valves 10 and 13 the motor cooling water is circulated through the pipe 9 into the expansion tank 5 and from thence by means of the connection 14

intermediate of the tank 5 and pipe 11 is returned directly to the suction side of the pump 3.

A common expansion valve is indicated at 15, by which the liquid is converted into gas while passing therethrough, and 16 illustrates a three-way valve for control of the passage of the liquid either through the expansion valve 15 and into the radiator 4 by way of the pipe connections 17—18 or through the branch pipe 19 to the coil 20 within the auxiliary expansion tank 5.

There are also illustrated at 21 and 22 common electrically operated control valves to be of the well known solenoid type, having suitable electric connections indicated at 23 and 24 to the vehicle battery 25 via the ignition switch 26 of the vehicle, so that these valves are simultaneously controlled by the ignition switch 26, thus insuring safety against leakage of gas.

With the above described mechanism it becomes possible to operate the device optionally; that is, either for heating or cooling of the body of the vehicle, or any special division of the body portion, wherein it becomes desired to control the temperature thereof, and which is accomplished in the following manner:

To use the device as a cooling medium, the control valves 21 and 22 of the system herein described are opened, this being accomplished automatically as previously described, when circulation of the liquid to the expansion valve 15 will take place (provided, of course, the three-way valve 16 is adjusted for such circulation, and it is desired to cool the compartment about the radiator 4); and the shut-off valves 10 and 13 will be closed, when the liquid in the radiator 4 will become cold on account of the expansion taking place in the coils therethrough of the pipe 18, it being understood that the upper and lower compartments 27 and 28, respectively, of the radiator 4 are connected by vertical tubes 29 through which the loops or coils of the pipe 18 pass, the outside atmosphere readily circulating through the openings 30 in the radiator, there being, of course, the usual fan, not shown, for circulation of the air therethrough at the will of the operator. In this event the water from the motor and radiator 2 will be normally circulated through the pipe 9, auxiliary tank 5, and pipes 14 and 11, to the pump 3, added expansion of the gas in the pipe 19 and coil 20 taking place by virtue of the warm water passing through the tank 5, the latter of course, being at this time cooled. Whereas when it is desired to heat said compartment the valves 10 and 13 are opened and the three-way valve 16 adjusted to admit the

gas directly into the pipe 19 and coil 20 in the tank 5, when hot water will be circulated through the radiator 4, pipes 12 and 11 to the suction side of the pump 3, and at which time some circulation of the hot water will pass through the pipe 9, or a shut-off valve may be installed in said branch pipe if desired.

- Having thus described my invention, what I claim and desire to secure by Letters Patent, is:
- 5 1. In an air conditioning system for automobiles, having a motor, radiator, carburetor and water circulating pump therefor, an air conditioner in the housing compartment of said automobile, a compressed liquid gas supply, an expansion tank for the gas supply, a circulating pipe leading from the gas supply to and through said air conditioner, thence to said expansion tank and to said carburetor, a valve to optionally connect the gas supply direct with the expansion tank, or through said air conditioner thereto and water circulating pipes connecting

the radiator, motor, expansion tank, pump, and air conditioner, whereby the body of the automobile may be optionally heated by the water of the circulating system or cooled by the expanding gas as it passes to the carburetor.

5

2. In an air conditioning system for automobiles having a motor, radiator, carburetor, and pump therefor, an air conditioning radiator within the body of the automobile, a liquid expansible gas supply for operating said motor, said gas supply being selectively connected with said air conditioning radiator, an expansion tank through which the fuel gas flows to the carburetor, a liquid circulating system for cooling the motor and selectively connected with said air conditioning radiator, whereby the body of the automobile may be optionally heated by the water of the circulating system or cooled by the expanding gas as it passes to the carburetor.
